DESIGN FOR A FOAM GENERATING APPARATUS

Richard L. Tuve, Silver Spring, Md.

Application August 30, 1945, Serial No. 121,756

Term of patent 3½ years

(Cl. D16—2)

To all whom it may concern:

Be it known that I, Richard L. Tuve, a citizen of the United States, residing at Silver Spring, in the county of Montgomery, and the State of Maryland, have invented a new, original, and ornamental Design for Foam Generating Apparatus, of which the following is a specification, reference being had to the accompanying drawings, forming a part thereof.

Figure 1 is a side elevation of a foam generating apparatus showing my new design.

Figure 2 is a front end elevation thereof.

Figure 3 is a rear end elevation thereof.

The invention described herein may be manufactured and used by or for the Government of the United States of America for governmental purposes without the payment of any royalties thereon or therefor.

I claim:

The ornamental design for a foam generating apparatus, substantially as shown.

RICHARD L. TUVE.
